UNITED STATES PATENT OFFICE.

ROBERT J. FIELDS, OF BALTIMORE, MARYLAND, ASSIGNOR OF ONE-HALF TO CHARLES C. FIELDS, OF BALTIMORE, MARYLAND.

SHIRT.

1,276,631.

Specification of Letters Patent.

Patented Aug. 20, 1918.

Application filed November 7, 1917. Serial No. 200,650.

To all whom it may concern:

Be it known that I, ROBERT J. FIELDS, a citizen of the United States, residing at Baltimore, in the State of Maryland, have invented certain new and useful Improvements in Shirts, of which the following is a specification.

This invention relates to certain improvements in shirts for men and boys.

10 An object of the invention is to provide ordinary shirts with means applicable to the lower part of the shirt, which will hold the said lower parts of the shirt from rising at the belt-band and pulling out of the trousers.

15 A shirt provided with the improvement constituting the present invention, is illustrated in the accompanying drawing, in which—

20 Figure 1 is a front-view of a shirt to the lower edges of which two thigh-bands are applied.

25 Fig. 2 is a back view of the lower part of a shirt and showing the thigh-band feature of the present invention, the same being in closed position to hold the shirt down.

Fig. 3 is a front view of the lower parts of a shirt; in this case the thigh-bands are in the unfastened position.

30 Fig. 4 is a bottom view on a larger scale of one of the thigh-bands and binding.

In the present instance, the shirt shown in the drawing for the purpose of illustrating the invention, is of the type called a "coat shirt" because at the front it has a central 35 vertical opening from the neck-band to the bottom edge of the shirt. But it is to be understood this particular type or style of shirt is unimportant and other styles of shirts may have the present improvement applied just as well.

The shirt back 5, has at its lowermost part and midway between the two side edges a portion of the fabric cut away and removed to form an inverted-V notch, 6. The 45 edge of the notch has a binding 7. The shirt front, 8, has at its lowermost part and midway of the two side edges, x—x a depending apron, 9; this formation of shirt apron at the center is produced by cutting a 50 right-angled piece of fabric and removing same from the front of the two side edges and at the bottom, which cutting leaves two right-angled notches, 10, one being at each lowermost corner.

The particular style of shirt shown in the 55 drawing has at the front a central vertical opening, 11, extending to the bottom-edge of the shirt, said vertical opening or slit divides the short apron, 9, at its middle; in Fig. 3 one half of the apron 9, is shown 60 hanging down and the other half is shown turned upward.

A woven fabric stay-strap or binding, 12, is sewed to the bottom edge of the shirt-back 5, and said binding extends around 65 to the edge of the right-angled notches, 10, at the front to which said binding is also sewed. This produces two bindings, 12, one at the outer side of each hip of the wearer; each binding has two terminal ends, or tabs, 70 13, each being provided with two button-holes, 14, separated by a longitudinal space 15.

An elastic thigh-band, 16, has its two ends suitably connected with the two terminal 75 ends, or tabs, 13, of the binding 12. Preferably the means for effecting this connection should be such as will permit the thigh-bands to be readily disconnected. In the present instance each tab-end 13 is folded 80 at the separating space, 15, so as to bring the two button-holes, 14, into coincidence one tab-end is then slipped through a coupling link, 17, which is attached to one end of the thigh-band 16, see Fig. 4, and the tab-end folded flat, then a shanked button, 18, is slipped through both holes, 14, on the tab; by this action the tab, 13, forms a loop, 19, that connects with said link, 17. The other end of the thigh-band, 16, is similarly fas- 85 tened to the binding, 12, except that this last mentioned end of the band should be ar- ranged to permit adjustment that will cause the thigh-band to fit around the person's 90 thigh as loosely or tightly as he may desire. 95 Any well-known kind of buckle will serve this purpose.

The shirt is put on the person over an undershirt, and the two binding bands, 12, will take position just below the two hip-joints 100 of the person; then each thigh-band of the shirt will be placed in position at the inner side of the person's thigh, and said bands be properly fastened to the binding bands. When the lower part of the shirt is tucked 105 into the top of the trousers this thigh-band device will prevent the shirt from working upward or pulling out.

Having described my invention I claim—
A shirt having a central vertical opening at its front and a notch formed at each of the two lowermost corners thereof leaving the lowermost midway part of the front dependent to form an apron; a woven fabric binding at each of said front notches, and extending around the bottom to the said back and each binding having two terminal

10 tabs; and two elastic thigh-bands each connected to said terminal tabs of the binding at the right and left sides respectively, to prevent the shirt from working upward on the person or pulling out of the trousers.

In testimony whereof I affix my signature in the presence of two witnesses.

ROBERT J. FIELDS.
